(57) **CLAIM**

The ornamental design for a compression relief brake assembly, as shown and described.

DESCRIPTION

FIG. 1 is a front perspective view of the compression relief brake assembly of the present invention.

FIG. 2 is a rear perspective view of the compression relief brake assembly of the present invention.

FIG. 3 is a rear elevation view of the compression relief brake assembly of FIG. 1.

FIG. 4 is a right side elevation view of the compression relief brake assembly of FIG. 1.

FIG. 5 is a left side elevation view of the compression relief brake assembly of FIG. 1.

FIG. 6 is a top elevation view of the compression relief brake assembly of FIG. 1.

FIG. 7 is a bottom elevation view of the compression relief brake assembly of FIG. 1; and,

FIG. 8 is a front elevation view of the compression relief brake assembly of FIG. 1.

FIGS. 1-8 show portions of the compression relief brake assembly and its environment during use in phantom lines. The phantom lines show elements that form no part of the claimed design.

1 Claim, 3 Drawing Sheets
